UNITED STATES PATENT OFFICE.

ANTHONY MILLER AND HENRY RUMPEL, OF MILWAUKEE, WISCONSIN.

CHRISTMAS-TREE STAND OR HOLDER.

1,124,780.

Specification of Letters Patent.

Patented Jan. 12, 1915.

Application filed May 13, 1914. Serial No. 838,283.

To all whom it may concern:

Be it known that we, ANTHONY MILLER and HENRY RUMPEL, citizens of the United States, residing at Milwaukee, in the county of Milwaukee and State of Wisconsin, have invented certain new and useful Improvements in Christmas-Tree Stands or Holders, of which the following is a specification.

This invention relates to Christmas tree stands or holders, and its primary object is to provide a device of this character which is simple of construction, neat and ornamental in appearance, convenient and efficient in use and adapted to be economically manufactured.

A further object of the invention is to provide a stand or holder which is adapted to contain a store of water for absorption by the tree, so that it will preserve a life-like appearance, and which is also adapted for the reception of a weighty substance to counterbalance the weight of the tree and provide a firm support without the necessity of fastening the stand or holder to a floor or other foundation.

The invention consists in the features of construction, combination and arrangement of parts hereinafter described and claimed, reference being had to the accompanying drawings, in which—

Figure 1 is a central vertical section through a Christmas tree stand or holder embodying the invention; and Fig. 2 is a top plan view of the same.

In carrying the invention into practice, we provide a stand or holder comprising a frusto-conical vessel 1, preferably made of sheet metal and designed to contain a suitable quantity of water 2. The vessel is provided with an opening in its top, through which the water may be discharged and whereby the interior of said vessel may be cleansed when required. The enlarged cover 3 is provided to close this opening,

and this cover may have a filling aperture 4 through which the water may be introduced when the stand is set up and the cover is in position, which opening may be closed by a screw-cap or other suitable closure 5.

The bottom or base of the holder is formed to provide a chamber or compartment 6, separated from the body or water-containing space of the holder by a wall, partition or diaphragm 7. This compartment 6 is adapted to receive a charge of

some weighty medium 7, such as sand or the like, the weight of which, added to the weight of the body of water 2, will counterbalance the weight of the tree, so that the stand or holder will firmly support the tree in position without the necessity of fastening such stand or holder to a floor or other base support. The chamber 6 is provided at one side with a tube 8 by which it may be filled or emptied, and it is normally closed by a cap or other suitable closure 9.

The cover 4 is centrally apertured, as shown at 10, for the reception of a receiving tube 11, which is designed to receive the limb or trunk of the tree and which fits at its upper end within a reinforcing band or collar 12 soldered or otherwise fastened to the cover, said tube and reinforcing band being provided with threaded apertures to receive screws 13 whereby the tree may be clamped in position. The tube is preferably of tapered form and contracted in a downward direction so as to receive the trunks of trees of different sizes, allowing one and the same holder to be employed as a support for different sized trees, but it will be understood that the stands or holders may be made of different sizes for the purposes stated, if desired. The tube is provided with a base plate 14 to rest upon the wall or diaphragm 7, whereby it is firmly stayed or braced, and this brace plate is formed with openings 15 to prevent the formation of a vacuum between the stem and diaphragm, whereby separation of the tube from the vessel may be easily effected. The tube is removable with the cover and is provided in its sides with openings 16 for the play of the water thereinto, so that the water will come into contact with the inserted trunk of the tree for absorption by the tree, thereby preventing the tree from drying out and thus preserving a life-like appearance.

A tree stand or holder constructed in accordance with this invention may be economically manufactured and sold at a low cost, is not unattractive in appearance, and affords the numerous advantages stated. It will, of course, be understood that while the structure shown is preferred, modifications of various kinds, within the scope of the appended claims, may be made without departing from the spirit or sacrificing any of the advantages of the invention.

We claim as our invention:

1. A Christmas tree stand or holder comprising a vessel adapted to contain water, a receiving tube depending into the vessel, 5 said tube having water inlets, and a hollow base for the vessel adapted to receive a weighty material and having means for the introduction and discharge of such material.
- 10 2. A Christmas tree stand or holder comprising a vessel adapted to contain water, a cover for closing said vessel, a tapered receiving tube extending through the cover into the vessel and provided with water inlets, and a hollow base for the vessel adapted 15 to receive a weighty material and having means for the introduction and discharge of said material.
3. A Christmas tree stand or holder comprising a vessel adapted to contain water, a 20 cover for closing said vessel, said cover being provided with a filling inlet, a tapered receiving tube extending through the cover and depending into the vessel, said tube having water inlets, a perforated base plate 25 carried by said tube, and a hollow base for the vessel adapted to receive a weighty material and having means for the introduction and discharge of such material.

In testimony whereof we affix our signatures in presence of two witnesses.

ANTHONY MILLER.
HENRY RUMPEL.
